UNITED STATES PATENT OFFICE.

WALTER S. MOODY, OF LYNN, MASSACHUSETTS, ASSIGNOR TO THE
GENERAL ELECTRIC COMPANY, OF NEW YORK.

ELECTRIC TRANSFORMER.

SPECIFICATION forming part of Letters Patent No. 591,869, dated October 19, 1897.

Application filed May 20, 1897. Serial No. 837,368. (No model.)

To all whom it may concern:

Be it known that I, WALTER S. MOODY, a citizen of the United States, residing at Lynn, in the county of Essex, State of Massachusetts, 5 have invented certain new and useful Improvements in Transformers, (Case No. 437,) of which the following is a specification.

The present invention relates to transformers specially intended for very high voltages, 10 as twenty thousand to thirty thousand volts, for example, and has for one of its objects to so arrange the energizing-coils that they are well insulated from the surrounding core and from each other, at the same time providing 15 suitable means for ventilation.

The invention also has for its object to provide a transformer having two complete and separately-controlled systems of cooling, one being for the coils and the other for the laminated core.

In the accompanying drawings, attached to and made a part of this specification, Figure 1 is a vertical section of my improved transformer. Fig. 2 is a plan view with top removed, and Fig. 3 is an enlarged cross-section taken through a portion of the coils.

The transformer is supported by a rectangular base A, provided with openings B at its ends to permit inspection of the secondary 30 terminals C. Shoulders B' are formed on the base, which support the laminæ D, which are insulated from the base by pieces of wood A'. Extending laterally within the base is a connection-board A², forming a support for the 35 secondary terminals C. The base is provided with an open-bottom chamber R, through which a current of air or other insulating medium enters the transformer-casing, as herein described. On the right and at the 40 upper end of the chamber R is a passage E, communicating with the chamber E'. To vary the opening in the passage, a regulator F is provided which consists of a rectangular casting having a number of openings and transverse gates. This casting is adapted to be 45 moved backward and forward over a similar construction on the base.

The laminæ are divided into sections, and the sections separated from each other by 50 space-blocks, which are so arranged that ventilating-spaces G are left between the sec-

tions. These ventilating-spaces extend parallel to the laminæ and communicate with chambers H and E', but are entirely separate from the ventilating-spaces between the coils, 55 as will be hereinafter explained. The chambers E' and H are formed by sheet-iron covers k and l, which extend from the base A to the top J. The chamber E' is separated from the chamber H by pieces of non-magnetic material m and n, situated at opposite ends of the transformer, so that the two chambers communicate only through the ventilating-spaces in the core. The casing which forms chamber H is perforated so that air or other insulating medium received from the chamber 65 E through the spaces G will pass to the outside.

Owing to the large size of the transformer, it has been found desirable to divide the 70 laminæ into two bodies which are separated by a slight space, Fig. 2. Each of these bodies is built up separately around the coils which form the primary and secondary.

To secure the laminæ together, a cast-metal 75 top J is provided, having inwardly-projecting flanges which are insulated from the laminæ by blocks of wood J'. To clamp the top to the base, two vertically-extending bolts J² are employed, one on each side of the core. 80 The nuts employed to secure the top are situated on the outside, so that they are readily accessible. By this arrangement they may be adjusted or removed without endangering the insulation of the coils by the use of wrenches. 85

Mounted on the top is a removable cover K, which is provided with a series of openings K' and a slide K², adapted to vary the extent of the openings by moving back and forth like a stove-damper. This regulates the amount 90 of air that passes through the air-chambers between the coils.

In transformers intended for very high voltage, a large amount of insulation is required between the primary and secondary 95 coils, and where this insulation is applied directly to the coils it is very difficult to keep the temperature of the transformer down to a proper degree, owing to the slowness with which heat can be absorbed from the coils 100 through the insulation. To overcome this objection, I form the coils into any desired

shape, the turns being insulated from each other in the usual manner, and the coil as a whole may be covered by tape or other insulation, but preferably such insulation is limited in amount. The insulation required to insulate the turns from one another and any additional insulation applied, when desired, directly to a complete coil will be relatively small compared with what would be necessary to form a safe insulation between the primary and secondary coils or between the primary coils and the core, and will not prevent the absorption of heat to any considerable extent. The coils are now mounted in a suitable casing L, extending from the top lengthwise into the chamber R at the bottom of the transformer and cutting off the coils with their system of ventilation from the chambers E' and H and the core system of ventilation.

The primary and secondary windings are subdivided into a number of coils which are distributed in any desired manner. This is best shown in Fig. 1, where there is first a secondary coil S, likewise in two sections, then another similar primary coil, and lastly a secondary coil. These windings as a whole are separated from the core by the casing L, of leatheroid or fiber, as described.

The primary coils are insulated from the secondary coils and case in a novel manner designed to afford ventilating-spaces between the coils and the bulk of the insulation, and preventing heating of the coils to a very material extent as compared with previous constructions. This is best shown in Fig. 3, to which reference is now made.

The primary coils P consist of a number of turns of flat wire or ribbon with suitable insulation between the turns. A small amount of insulation a is placed between the two sections which form one coil, and the two sections are then given a covering b of tape to hold them together. At the edges of the coils is insulation N, consisting of U-shaped pieces of leatheroid. Outside of this is placed a single layer of insulation c with its ends overlapping, and the whole bound together by a band of tape d. The insulation c is separated from the coils by a block of wood g, and a similar block is placed between the coils. Situated on both sides of the primary coils are secondary coils S. These are similar in construction to the primary coils. These coils are insulated at their edges by U-shaped pieces of insulation e, and between this insulation and the inclosing case of the primary is a strip f. A block of wood g is placed between the coil and the primary case to hold them in position. It will be seen that the leatheroid c and the tape d serve as a partition between the passages O and Q. The insulation thus applied forms a sort of open-work structure having a number of channels or air-passages, preferably closed or substantially closed from one another, and open top and bottom to allow a free circulation of air

between the different windings and between the coils and insulation. The insulation forming the walls of these channels preferably extends beyond both ends of the coils, so as to present an extended creeping-surface over which current must pass before it can reach the secondary winding. There being no especial reason for economizing space at the ends of a transformer, the casings can be extended to a point where the insulation will be as high, or even higher, than that at any other point between the primary and secondary windings.

The inclosing case L consists of sheets of insulating material h, and surrounding it is a layer of tape i. This completely insulates the coils from the core. Air or other insulating fluid, upon entering the chamber in the base, passes upward through the passages between the coils in a vertical direction, and the amount is regulated by the damper located in the cover K. At the same time a portion of the air or other insulating medium passes up through the damper E into chamber E' and passes through the passages G to the chamber H and to the outside of the case in a direction transverse to that which flows upward through the coils.

It will be seen that there are two separate ventilating systems for cooling the transformer, one for the coils, the other for the iron, and that each of them is controlled independently of the other.

What I claim as new, and desire to secure by Letters Patent of the United States, is—

1. In a transformer, the combination of a core, primary and secondary windings and insulation for insulating the primary winding from the secondary winding, not applied to said windings direct or either of them, but separated from the windings and permitting a more ready absorption of the heat developed in the windings, as set forth.

2. In a transformer, a primary or high-potential winding surrounded by a heavy insulation which is separated from the winding by an air space or spaces, said insulation serving to insulate the primary from the secondary winding.

3. In a transformer, a primary or high-potential winding subdivided into sections slightly separated from one another, and an insulating-casing surrounding said winding and separated therefrom by an air space or spaces, said casing serving to insulate the primary from the secondary winding, as set forth.

4. In a transformer, the combination of primary and secondary windings with passages extending between the windings for the circulation of a cooling medium, and a laminated iron core with a second set of passages, through which circulates an insulating cooling medium, said sets of passages forming independent cooling and ventilating systems, one for the coils and one for the core.

5. In a transformer, the combination of pri-

- mary and secondary windings, a laminated iron core, passages extending between the windings through which an insulating medium circulates to cool the windings, a second set of passages extending through the iron core independent of the first, in which an insulating medium circulates to cool the iron, and means for regulating the circulation through both sets of passages.
6. In a transformer, the combination of primary and secondary windings, a laminated core, means for maintaining an up-and-down circulation of air through the coils, and means for maintaining a transverse circulation of air through the iron core, both circulations being independent.
7. In a transformer, the combination of primary and secondary windings separated by air-passages, a laminated core divided into sections, and air-passages independent of those between the windings formed between the sections, a common source of air-supply, and means for regulating the flow of air through each set of passages independently.
8. In a transformer, the combination of primary and secondary windings, divided into a number of coils, a laminated iron core, an insulating-case surrounding one or more of the coils and provided with open ends at the top and bottom, and spaces between the coils for the free circulation of an insulating medium.
9. In a high-potential transformer, the combination of an insulating-casing surrounding the primary and secondary windings, with vertically-extending air-spaces between the coils and the case, an insulating-case mounted within the first and surrounding one of the windings, and air-spaces between the last-mentioned winding and its surrounding case, the two sets of air-spaces being independent.
10. In a high-potential transformer, the combination of primary and secondary windings, each composed of a number of turns of wire which are sufficiently insulated to prevent leakage between adjacent turns, but not enough to insulate them from the core and the other winding, a body of insulating ma-

terial located between the windings, and spaces formed between the windings and the insulation for insulating the coil and permitting the circulation of an insulating and cooling medium.

11. In a high-potential transformer, the combination of primary and secondary windings divided into sections, a laminated core, an insulating-case between the core and the windings, air-passages between the case and the windings, insulating-cases surrounding the primary winding and separating it from the secondary, the cases being provided with open ends which project above and below the ends of the coils so as to increase the creeping or leakage surface, air-passages between the primary coils and the casings, and a common chamber supplying air for both sets of passages.

12. In a transformer, the combination of primary and secondary windings separated by air-passages, a laminated iron core divided into sections, a set of air-passages between the sections and independent of the first, an air-chamber in the base supplying air to the passages between the windings, and a chamber located on one side of the laminæ and connecting with the chamber in the base for supplying air to the passages between the core-sections.

13. In a transformer, the combination of primary and secondary windings, a laminated iron core, air-passages extending in a vertical direction through the windings, air-passages extending through the iron in a direction transverse to and independent of the first set, an air-chamber in the base, a chamber located on one side of the core communicating therewith and supplying air to the core-passages, and means for regulating the passage of air through both sets of passages independently.

In witness whereof I have hereunto set my hand this 18th day of May, 1897.

WALTER S. MOODY.
